ELECTRIC HEAD LAMP PROJECTOR AND
INCANDESCENT LAMP THEREFOR

Reginald K. Braunsdorff, East Orange, N. J.; assignee to Tung-Sol Lamp Works, Inc., Newark, N. J., a corporation of Delaware

Application September 28, 1944, Serial No. 556,115

31 Claims. (Cl. 176—34)

1

This invention relates to electric headlamp projectors and incandescent lamps therefor.

A parabolic reflector with a point light source at the focus would give a circular parallel beam of reflector diameter. A point source is not available in practice as all conventional filaments possess mass and size which disturbs such theoretical projection. The size of the filament (which includes number of turns, length of barrel and diameter of coil) influences the spot or beam pattern obtained. Different kinds of reflectors have been proposed and various lenses have been proposed for modifying the beam or pattern furnished by the reflector.

One object of the invention is an incandescent filament lamp for reflector or headlight use embodying a coil filament of distorted form for obtaining a headlight beam pattern which approximates more nearly the desired pattern thereby minimizing the importance or necessity for the provision of a special modifying lens.

A further object of the invention is an electric incandescent lamp of the above indicated character having a continuous coil filament which is distorted or irregularly formed at different portions of its length and may be wound on a single mandrel at a single operation.

A further object of the invention is a combined reflector of the conventional parabolic form and an electric incandescent lamp source of the above indicated character mounted in the reflector so as to assist in obtaining the desired beam pattern.

Further objects of the invention will hereinafter appear.

For a better understanding of the invention, reference may be had to the accompanying drawing, forming a part of this application wherein,

Fig. 1 is a view diagrammatically illustrating one embodiment of the invention;

Fig. 2 is a diagrammatic view of another modification of the invention;

Figs. 3 to 8 are diagrammatic views of other modifications of the invention;

Fig. 9 is a diagrammatic view of an electric incandescent lamp of the general character shown in Fig. 1 mounted in a conventional parabolic reflector, together with a beam pattern which may be approximated by suitably mounting the lamp in the reflector;

Fig. 10 is a similar diagrammatic view of an incandescent lamp of the general character shown in Fig. 2; and

Fig. 11 is a view of a still further modification.

2

For vehicle road lighting generally a beam pattern is desired which is cut off in the upper left section looking in the direction of travel so as to provide lower light output in the upper left section, and higher light output in the upper right section. Two shapes of such beams are shown diagrammatically in Figs. 9b and 10b but it is understood that these beams thus schematically shown are intended to illustrate only the general shape and not accurately to indicate the exact details of the beam pattern.

The beam pattern shown in Fig. 9b is of substantially less depth on the left than it is on the right. Such a beam may be approximated by utilizing in the reflector diagrammatically shown at 1 a specially constructed filament 2. This filament is of small coil diameter at its righthand end and of larger coil diameter at its lefthand end, looking down on the reflector. The filament of that embodiment is of multiple coil diameter parts, there being two such parts 3 and 4. In the particular embodiment shown the parts 3 and 4 of the filament have a common axis (Fig. 1) and the part 3 is longer than the part 4, roughly three times the length thereof and having approximately three times the number of turns embodied in the larger end 4 of the filament. The relative lengths of the distorted parts of the filament 2 may be varied to suit the requirements, as for example, the large part 4 might be provided in one or two turns or four or more turns instead of the three and a half turns indicated, and likewise the small part 3 of the distorted filament may be of a different length and a different number of turns from that indicated in Figs. 1 and 9.

The filament 2 is mounted in the bulb or envelope 5 and the lamp is then mounted in the reflector 1 so as to produce or approximate the beam pattern desired, for example, by positioning the lamp 5 so as to have the filament 2 bearing a definite relation to the focal point of the reflector, as for example, with the focal point of the reflector disposed intermediate the length of the coil 2 and on the common axis thereof. A beam pattern generally like that shown in Fig. 9b may be approached having an enlarged part 4' on the right and a part of smaller depth 3' on the left, looking in the direction of the projected beam. The enlarged part 4' of the beam pattern is produced by the part 4 of the larger diameter portion of the distorted filament but on the opposite side of the forward vertical plane passing through the focal point of the reflector, and similarly the small part of the beam pattern

is produced by the small diameter part 3 of the distorted filament but likewise on the opposite side of that vertical plane. As above pointed out, the beam pattern shown in Fig. 9b is not intended to be an exact mathematical illustration of the actual beam produced but is intended as an illustration merely of the general shape contrasting the widely varying parts of the pattern. In the particular embodiment illustrated in Fig. 9 the lamp 5 is mounted in the reflector 1 with the common axis of the filament 2 disposed substantially horizontal but by orienting the lamp so as to incline this axis of the filament 2 to the horizontal plane the parts 3' and 4' of the beam may be varied in a vertical plane relatively to each other, as for example so as to elevate the righthand portion 4' of the beam pattern with respect to the parts 3', thereby bringing the bottom edge of the pattern to approximately the horizontal position. Likewise different beam pattern effects may be obtained by shifting the distorted filament 2 with respect to the focal point of the reflector and by combining these two adjustments other beam pattern effects may be produced.

In the embodiment of Fig. 10 the beam pattern shown in Fig. 10b has a common bottom cut-off line 6 for both the right and left hand parts of the beam, with the filament 7 disposed substantially horizontal. A beam of this general shape, looking in the direction of the beam projection, may be approximated by distorting the shape of the filament 7 as shown in Figs. 2 and 10a. In this embodiment the filament coil is also provided with different coil diameter parts at its ends, the right-hand part 8 of the filament being of small diameter, while the part 9 on the left is of relatively larger diameter, but here the axes of the two filament parts 8 and 9 are relatively offset with the edges of the turns of the parts 8 and 9 being disposed in line on one side. In Fig. 2 the axis of the part 9 of the filament is shown in broken lines while the axis of the part 8 of smaller diameter is illustrated in a dot-and-dash line. The part 9 of the filament assists the reflector in producing the part 9' of the beam pattern, while the part 8 assists in producing the part 8' of the beam pattern (Fig. 10b). The focal point of the reflector 1 may be disposed roughly midway the length of the filament coil 7 and between the axes of the coil parts 8 and 9 and by the use of a parabolic reflector 1 or reflector generally of that construction or of the conventional type, the beam pattern parts corresponding to the particular parts 8 and 9 of the filament are produced on the opposite sides of the vertical plane passing through the axis of the reflector. This pattern corresponds generally to the positioning of the filament about the focal point as described, with the axis of the filament part 9 disposed below the axis of the filament part 8, namely with the filament part 9 being predominantly below the horizontal plane through the axis of the reflector, while the filament part 8 is generally symmetrical with respect to that plane. The pattern may be varied by mounting the filament in the reflector so as to have the axes of the filament parts offset from each other in any desired direction.

The pattern shown in Fig. 10b may be varied by changing the filament 7 relatively to the focal point, that is by changing the vertical or horizontal positioning with respect to the focal point or by a combination of these adjustments

or by rotation of the bulb 5 about its axis in the reflector. In the particular embodiment shown the length of the small diameter part 8 is greater than the length of the large diameter part 9 and also in this particular embodiment the part 8 has roughly twice the number of turns and is roughly twice the length of the large diameter part 9 but it is understood that the number of turns of each of the parts 8 and 9 may be varied to suit any particular requirements.

In the embodiments illustrated in Figs. 1, 2, 9 and 10, the diameter of the filament parts 3 and 8 is roughly one-third the diameter of the larger diameter parts 4 and 9 respectively of the filaments. Also in the particular embodiments shown the filaments are constructed with steps in diameter, as distinguished from tapered coils with a uniform variation in diameter from one end to the other. But it is understood that certain advantages of the invention may be obtained with variations in the structure of the filaments, the relative arrangement thereof with respect to themselves and to the focal point of the reflector, etc.

The filament embodiments of Figs. 3 to 8 show different forms of continuous coil distorted filaments. In Fig. 3 the parts 8 and 9 of the filament 7 are like the embodiment of Fig. 2 shown of uniform diameter turns but are reversely positioned with respect to that illustrated in Fig. 2. In Fig. 3 the axis of the part 8 which is illustrated in dot and dash lines is illustrated to be displaced with respect to the axis of the part 9 which is illustrated in broken lines, which is in reverse position of that shown in Fig. 2.

In the embodiment of Fig. 4 the continuous coil distorted filament 10 has its turns gradually increasing in diameter from the small end 11 to the large end 12 and the increase in diameter is not uniform but the increase in diameter is according to a mathematical curve as indicated by the tangent CD touching the rearward edges of the filament turns. The axis of the filament 10 is shown in the dot-and-dash line.

In the embodiment of Fig. 5 the distorted filament 13 is provided with turns gradually increasing in diameter from the small end 14 to the large end 15 and here the filament is unsymmetrical with respect to the axis EF of the small end of the filament, the axis FG of the filament 13 being inclined to the axis EF and the rear edges of the turns forming the filament coil are tangent to the vertical transverse plane parallel with the axis EF. This is in contrast with the symmetrical filament 10 of Fig. 4 whose turns are formed symmetrically about the axis EF of the smaller end of the filament. In the embodiment of Fig. 5 the axes EF and GF are illustrated as being in a plane parallel to the plane determined by the legs A and B of the filament. In the embodiments of Figs. 2 and 3 the axes of the filament parts 8 and 9 are also disposed in a plane parallel with the legs A and B.

In the embodiment of Fig. 6 the continuous coil distorted filament 16 is formed of two parts 17 and 18 which parts are in turn formed of turns of uniform diameter similarly to the embodiments of Figs. 1, 2 and 3. Instead however of the axes of the filament parts 17 and 18 being coincident as in Fig. 1, they are offset from each other but in a specifically different manner as shown by the lefthand part of Fig. 6, so that as viewed in the righthand portion of Fig. 6 the axes of the two parts 17 and 18 appear to be coincident. Here the axis of the small diameter

part 17 of the filament is parallel to the plane determined by the legs A and B and likewise the axis of the large part 18. The centers of the parts 17 and 18 are indicated respectively at H and K in projection to the left of Fig. 6.

In the embodiment of Fig. 7 the filament 20 is provided with a small diameter part 21 and a larger diameter part 22 at the ends with an intermediate part 23. The part 21 is of uniform diameter and the part 22 is of uniform diameter but the intermediate part 23 is of varying diameter so as to merge the end parts 21, 22 gradually into each other. In the embodiment of Fig. 8 the filament 25 is formed of a small diameter part 26 and a larger diameter part 27 respectively formed at the ends. The small diameter part 26 is of uniform diameter turns. The larger diameter part 27 is formed with flat-sided turns, the flat side being indicated at 27'. Assuming the mounting is such that the flat side of the large diameter part 27 is on the under side of the filament 25 shown in Fig. 8, the axes of the parts 26 and 27 are displaced from each other in a vertical plane. In the righthand portion of Fig. 8 these axes appear coincident. The sides of the turns of the small diameter part 26 on one side are level with the surface of the flat side 27' of the large diameter turns, that is the plane including the surfaces of the flat sides 27' of the part 27 is tangent to the surfaces of the turns forming the coil part 26. The ends of the axes of the two coil portions are indicated at H and K.

It is understood that the continuous coil distorted filaments of Figs. 3 to 8 are mounted in a reflector of suitable type, as for example, one of the general parabolic type illustrated by the numeral 1 in Figs. 9 and 10. In each modification different forms of beam patterns may be obtained by mounting the filament or lamp bulb 5 in the reflector in such a manner as to obtain or approximate the desired shape pattern. As with the modifications of Figs. 1 and 2 (Figs. 9 and 10) different shape beams may be obtained by mounting the filaments of each of the modifications 3 to 8 in different positions relatively to the focal point of the reflector and the axis of the beam pattern may be adjusted as may be desired by rotating the lamp bulb 5 within the reflector to obtain the desired orientation of the pattern.

In the particular embodiments illustrated I have shown bulbs 5 embodying only a single distorted filament but in some cases it may be desired to mount two of these distorted filaments in the same bulb with the bulb mounted in the reflector so as to obtain a special beam pattern formed by the combined lighting effect of the two or more distorted filaments thus mounted with respect to the focal point of the reflector or special beams from the individual filaments. Such a lamp bulb is illustrated in Fig. 11 wherein a bulb is shown embodying two independently mounted continuous coil distorted filaments, being similar to the filament 2 of Fig. 1. It is understood that the lamp bulb here shown is mounted in a reflector of any suitable type, as for example, of the parabolic type indicated at 1 in Figs. 9 and 10 with the two distorted filaments 30 and 31 positioned with reference to the focal point of the reflector as may be desired to obtain or approximate the beam pattern desired.

Thus this invention makes it possible to obtain a beam pattern which is substantially different from the beam pattern furnished by the conventional filament lamps and accordingly an initial beam distribution unassisted by lens action is

obtained which, together with the particular reflector used, is either sufficient to give the desired beam pattern, or less lens action is required to give the exact beam pattern desired, thereby simplifying headlamp structures. In the particular embodiment shown in Figs. 1, 2, 9 and 10 the filament parts 3 and 8 of smaller diameter are somewhat smaller than the diameters of the coil filaments conventionally used in vehicle headlights, while the filament parts 4 and 9 are of substantially larger diameter.

The different embodiments of the invention indicate the wide variety of possible shapes of continuous coil distorted filaments and the possibilities of construction and flexibility afforded by the invention. Any part of the coil filament may be specially constructed as for example, with a flat spot (Fig. 8) or with a raised section at some individual point within the total coil length. The mass or space occupied by the filament may be varied together with its shape at different points in order to obtain the effect desired in the projection with parabolic reflectors and the like. As above indicated the inherent error in projection may be met by some special lens in the area which gave trouble in the projected beam but with my invention compensation may be made or approximated in the particular continuous coil filament shape and in the particular position in which it is mounted in the bulb. Moreover, it is entirely practicable to form continuous coil filaments of the shapes indicated by forming them on similarly shaped mandrels.

In each of the Figures 1 to 8 the portion of the figure to the left is an approximate correct projection of the large end of the filament with certain of the turns of the coil omitted in certain cases to simplify the drawings.

I claim:

- 40 1. In an electric headlamp, a reflector, an incandescent lamp in the reflector having a lighting beam filament of the continuous coil type, said filament having its end portions formed of different coil diameters and the whole filament being positioned in the vicinity of the focal point of the reflector and at an angle to the axis of the lamp with the different diameter end portions thereof disposed on the opposite sides of the reflector axis.
- 45 2. In an electric headlamp, a reflector, an incandescent lamp having a lighting beam filament of the coil type, said filament having its end portions formed of different coil diameters and the whole filament being positioned in the reflector in the vicinity of its focal point and at an angle to the axis of the lamp with the different diameter end portions thereof disposed on the opposite sides of the reflector axis, and said small diameter part having a larger number of turns than the number of turns in the larger diameter part.
- 50 3. In an electric headlamp, a reflector, an incandescent lamp having a lighting beam filament of the coil type and mounted in said reflector, said filament having end portions of different coil diameters and the whole filament being positioned in the vicinity of the focal point of the reflector with the focal point disposed at the axis of the smaller coil section, said filament portions having a common axis and disposed at an angle to the axis of the lamp with the different diameter end portions thereof disposed on the opposite sides of the reflector axis.
- 55 4. In an electric headlamp, a reflector, an incandescent lamp in said reflector having a light-

ing beam filament of the coil type, said filament having its end portions formed of different coil diameters and the whole filament being positioned in the vicinity of the focal point of the reflector, said filament parts having their axes offset with the different diameter end portions thereof disposed on the opposite sides of the reflector axis.

5. In an electric headlamp, a reflector, an incandescent lamp therein having a lighting beam filament of the coil type, said filament having its end portions formed of different coil diameters and the whole filament being positioned in the vicinity of the focal point of the reflector, said filament portions having their axes offset vertically with the different diameter end portions thereof disposed on the opposite sides of the reflector axis.

6. In an electric headlamp, a reflector and an incandescent lamp source having a lighting beam filament of the coil type disposed in the vicinity of the focal point of the reflector with the barrel of the coil disposed at an angle to the axis of the headlamp, the coils at certain parts of the filament being of different diameters with different diameter portions disposed on the opposite sides of the axis of the lamp so as to provide a filament at the focal point which is unsymmetrical with respect to the axis of the lamp.

7. In an electric headlamp, a reflector generally of the parabolic type and an electric incandescent lamp source having a lighting beam filament of the coil type with the whole thereof being disposed at or in the vicinity of the focal point of the reflector, said filament crossing the axis of the reflector at the focal point, said filament having portions on the opposite sides of the reflector axis which are unsymmetrically distorted with respect to each other so as to give a distorted drive beam pattern.

8. In an electric headlamp, a reflector generally of the parabolic type, an incandescent lamp having a lighting beam filament of the continuous coil type with the axis of the lamp being coincident with the axis of the reflector, the whole of said filament crossing the axis of the reflector at the focal point and having end portions of different coil diameters with one end portion of the filament disposed on one side of the vertical axial plane passing through the focal point of the reflector and the other end portion of the filament disposed on the other side thereof to produce a projected driving beam pattern of laterally elongated form with the lefthand end of the pattern being of substantially less depth than the right-hand end thereof.

9. An electric incandescent filament lamp for projectors comprising an elongated coil lighting beam filament provided with turns of different diameters at certain parts thereof with the whole thereof disposed in the vicinity of a point of the lamp axis, and said coil being disposed at an angle to, and passing through, the axis of the lamp with the turns of different diameters making the filament unsymmetrical with respect to such axis.

10. An electric incandescent lamp for electric projectors embodying an elongated coil lighting beam filament embodying at least two parts having turns of different diameters, with the whole thereof disposed in the vicinity of a point of the lamp axis, and said coil being disposed at an angle to the axis of the lamp with the turns of the different diameters on opposite sides of such axis.

11. An electric incandescent lamp for electric projectors embodying an elongated coil lighting

beam filament embodying at least two longitudinally disposed parts having turns of different diameters with the whole thereof disposed in the vicinity of a point of the lamp axis, said parts having a common axis angularly disposed with respect to the axis of the lamp, said parts making the filament unsymmetrical with respect to the axis of the lamp.

12. An electric incandescent lamp for electric projectors embodying an elongated coil filament embodying at least two parts having turns of different diameters, the axis of one of said parts being offset with respect to the axis of the other.

13. An electric incandescent lamp for electric projectors embodying an elongated coil filament embodying at least two parts having turns of different diameters, said parts having axes offset along the axis of the lamp.

14. An electric incandescent lamp for electric projectors embodying an elongated coil filament embodying at least two parts having turns of different diameters, said parts having axes offset along the axis of the lamp with the edges of the turns of the parts forming on one side a straight line.

15. An electric incandescent filament lamp for projectors comprising an elongated coil lighting beam filament whose turns increase in diameter from one end to the other, said coil filament passing through, and being disposed at an angle to, the axis of the lamp.

16. In an incandescent lamp for electric headlamps, a continuous coil driving beam filament whose turns differ in diameter from one end to the other with the rate of change in diameter increasing from one turn to the next.

17. In an incandescent electric lamp for headlamps, a continuous coil lighting beam filament whose turns increase in diameter from one end to the other in a uniform manner, said coil filament passing through, and being disposed at an angle to, the axis of the lamp.

18. In an electric incandescent lamp for headlamps, a continuous coil lighting beam filament having at least two parts differing in diameter of turns, the axes of the two parts being displaced in a plane at right angles to the axis of the lamp.

19. In an electric incandescent lamp for headlamps, a continuous coil filament whose end portions are formed of uniform and different diameters with an intermediate portion of turn diameters merging into the two end parts.

20. In an electric incandescent lamp for headlamps, a continuous coil filament having at least two parts of different turn diameters and one of said parts being formed with a flat side.

21. In an electric incandescent lamp for projector headlamps, a continuous coil lighting beam filament of elongated form disposed crosswise of the lamp axis but having all of its parts disposed closely to the point of the axis at the crossing point, said driving filament having end portions of different coil diameters with said portions disposed on the opposite side of the axis to provide an elongated driving beam pattern with one end thereof of substantially lesser depth than that of the other end.

22. An electric incandescent lamp for headlamps embodying an elongated coil lighting beam filament having at least two longitudinally spaced parts of turns of different diameters, said parts being disposed on opposite sides of a plane including the axis of the lamp, with the whole thereof being disposed in the vicinity of a point of the lamp axis.

23. In an electric headlamp for automobiles, a reflector, an incandescent lighting beam filament of the continuous coil type concentrated at the focal point of the reflector to produce a driving beam with a minimum of diffusion due to displacement of filament parts from the focal point, said filament having its end portions formed of different coil diameters with one end of the filament disposed on one side of the vertical axial plane through the focal point and the other end of the filament disposed on the other side thereof.

24. In an electric headlamp, a reflector generally of the parabolic type, a lighting beam incandescent filament of the continuous coil type in said reflector, said filament crossing the axis of the reflector at the focal point and having end portions of different coil diameters with at least the extreme end portions of the filament disposed on opposite sides of the vertical axial plane passing through the focal point of the reflector to produce a projected driving beam pattern of laterally elongated form with one end of the pattern being of substantially less depth than the other end thereof.

25. In an electric headlamp, a reflector generally of the parabolic type, a coiled incandescent filament light source located in the vicinity of the focal point of the reflector and having portions thereof of substantially different coil diameters with at least the extreme end parts of said source disposed on opposite sides of the vertical axial plane passing through the focal point of the reflector to produce a projected passing beam pattern of a laterally elongated form with the righthand end of the pattern looking in the direction of travel being of substantial depth to light up the righthand side of the road to a considerable vertical depth and with the lefthand end of the pattern being of substantially less depth to minimize glare to approaching drivers.

26. An electric incandescent projector lamp comprising a reflector and an elongated coil as the light source having turns of different diameters at certain parts thereof, said coil being disposed in the vicinity of the focal point of the reflector and transversely of and unsymmetrical to the longitudinal axis thereof.

27. An electric incandescent lamp for projectors having an axial lamp mount to produce a focused light beam, comprising an elongated coiled filament disposed transversely of the base of said lamp, said filament having turns of different diameters at certain parts thereof and unsymmetrically located relative to the longitudinal axis of the base.

28. An electric incandescent lamp for projectors, comprising an elongated coiled filament with the turns increasing in diameter from one end to the other, said filament disposed transversely of

10
5

the axis of the base of the bulb and in the vicinity of a point thereon whereby said lamp cooperates with the projector to produce a beam of light of elongated cross-section wherein one end portion thereof is substantially deeper than the remaining portion.

29. An incandescent projector lamp having a coiled incandescent filament, said filament comprising at least two portions of different diameter, whose longitudinal axes are substantially parallel and disposed transversely of the longitudinal axis of the base part which extends through the focal point of the projector, said filament axes being adjacent said focal point whereby an unsymmetrical focused light beam is produced.

30. An electric light projector in combination a reflector, and an elongated light source disposed transversely of the longitudinal axis of the reflector, said light source having different size light producing areas at different parts thereof to produce a beam of light unsymmetrical to the axis.

31. An electric light projector comprising a reflector, an elongated filament in said reflector disposed transversely of the longitudinal axis thereof, said filament having turns of different diameters at different parts thereof and supporting and electrical connecting means for the filament extending through and positioned in the rear of the reflector for connection to an electric circuit.
